(57) **CLAIM**

The ornamental design for a garage storage hook, as shown and described.

DESCRIPTION

FIG. 1 is a front perspective view of a garage storage hook, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines representing stitching are part of the claimed design. The broken lines that are not stitching illustrate portions of the article that form no part of the claimed design.

1 Claim, 7 Drawing Sheets
